United States Patent Office

Des. 181,146
Patented Oct. 8, 1957

181,146

DISPLAY SIGN

John A. Heard, San Antonio, Tex.

Application January 17, 1956, Serial No. 39,819

Term of patent 14 years

(Cl. D1—12)

Fig. 5.

Fig. 2.

Fig. 1.

Fig. 3.

Fig. 4.

Fig. 1 is a front elevational of a display sign embodying the invention of my new design.

Fig. 2 is an end view of the sign of Fig. 1 and taken from the left in Fig. 1.

Fig. 3 is an end view of the sign of Fig. 1 and taken from the right in Fig. 1.

Fig. 4 is a bottom plan view of the sign illustrated in Fig. 1.

Fig. 5 is a top plan view of the sign illustrated in Fig. 1.

The rear of the sign may be substantially like the side shown in the front elevational view of Fig. 1.

What is claimed is:

The ornamental design for a display sign, substantially as shown and described.
